UNITED STATES PATENT OFFICE.

ADOLPH NIFLOT, OF NEW YORK, N. Y.

FOUNTAIN-PEN BLOTTER.

1,010,676.

Specification of Letters Patent.

Patented Dec. 5, 1911.

Application filed February 28, 1911. Serial No. 611,500.

To all whom it may concern:

Be it known that I, ADOLPH NIFLOT, a citizen of the United States, residing at New York, in the borough of Manhattan, county 5 of New York, and State of New York, have invented certain new and useful Improvements in Fountain-Pen Blotters; and I do hereby declare the following to be a full, clear, and exact description of the invention, such as will enable others skilled in the art to which it appertains to make and use the same.

My invention relates to penholders and especially to a blotting attachment for fountain-pens. Its object is to provide a convenient blotter adapted to serve in the ordinary manner and also to prevent the soiling of hands, clothing or paper by any leaking of the fountain-pen.

20 To this end it comprises essentially a tube of blotting-paper adapted to fit over a penholder, and more particularly, in the form illustrated, having reduced walls at each end so that pockets are formed with especial 25 reference to the construction of a fountainpen.

In the drawing 1 represents the upper part of a fountain-pen and 2 a reduced or conical end of the upper part.

30 3 is the main barrel or ink-holder of the fountain-pen and 4 is the tapering or substantially conical pen-holding portion.

5 represents a tube of blotting-paper adapted to embrace closely the barrel 3 of the pen-holder.

35 6 is a portion of the blotting-paper tube

having a reduced wall so that a recess or enlargement is created which will permit the insertion of a cap, and which will, in any event, serve to receive and absorb any 40 ink which may leak from the pen or which may run down the part 4 of the pen-holder. 7 is a similar recess or enlargement at the opposite end of the blotting-paper tube.

It will be observed that when the cap 1 45 is in place there is a space between the junction of the cap and the barrel 3 which will permit the ready absorption of any oozing drop of ink. The inclosing tube 3 is adaptable also as a blotter for certain classes of 50 work. In this case the fountain-pen may be rolled over the surface bearing the writing:

When the blotting-paper tube has been stained or worn it may be renewed and a 55 new one substituted, the cheapness of the article, enabling frequent replacements of the old and soiled blotters.

I claim,—

The combination with a fountain-pen, of 60 a tube of blotting-paper having reduced walls at each end to form a receptacle to receive a cap and also to absorb any ink which may leak from the holder or accidentally escape from the pen. 65

In testimony whereof I affix my signature, in presence of two witnesses.

ADOLPH NIFLOT.
